UNITED STATES PATENT OFFICE.

RAPHAEL F. POLI, OF CAMP SCHUMWAY, COLORADO.

SAFETY ELECTRIC SWITCH.

Application filed January 18, 1922. Serial No. 613,375.

To all whom it may concern:

Be it known that I, RAPHAEL F. POLI, a citizen of the United States, residing at Camp Schumway, in the county of Huerfano and State of Colorado, have invented certain new and useful Improvements in Safety Electric Switches, and I do declare the following to be a full, clear, and exact description of the invention, such as will 10 enable others skilled in the art to which it appertains to make and use the same, reference being had to the accompanying drawings, and to the characters of reference marked thereon, which form a part of this 15 specification.

This invention relates to electric switches of the type in which the translating device circuit can only be connected or disconnected while the switch is open.

20 In mines, factories and other places where a machine is to be employed in different places it is common to provide a set of feeder mains extending throughout the mine or factory and to connect the machine 25 to the feeders at the most convenient place. I shall describe my invention as employed in coal mining, as I intend to use it in this relation although, as indicated above, it can be used in other places.

30 In coal mines a set of feeder wires are run through the main galleries for convenience in making connection to the electric drills, undercutters or other machines used in the mining operation. The machines are ordinarily provided with a long cable whose free 35 end is provided with clips or other means for making connection to the feeder circuit. It has frequently happened that when the operator connects the clips to the feeders 40 there is a short circuit on the line to the machine, or the machine may be of large current capacity and connected to the line. In either case there is a heavy flow of current as soon as the initial contact is made 45 which results in a heavy arc which temporarily and sometimes permanently blinds the operator. In the same manner, if the operator should attempt to disconnect the conductors from the feeders, before the 50 translating device is disconnected, an arc will be formed often with disastrous results.

It is a further object of this invention to provide a switch which can be opened and closed without danger of the operator coming 55 in contact with live parts. The above objects and others, which will appear as

the description proceeds, are attained by a construction which I will now describe, reference for this purpose being had to the accompanying drawing, in which:

Fig. 1 is a horizontal section through a portion of a coal mine and shows the relative location of the feeder circuit safety switch and the electric drills or other apparatus employed.

Fig. 2 is a central longitudinal section of my safety switch.

Fig. 3 is a horizontal section taken on line 3—3, Fig. 2.

Fig. 4 is a horizontal section taken on line 3—3, Fig. 2 and looking upwardly.

Fig. 5 is a transverse vertical section taken on line 5—5, Fig. 2, looking toward the right.

Fig. 6 is a transverse vertical section taken on line 6—6, Fig. 2, looking towards the left.

Fig. 7 is a plan view of the attachment plug with the upper portion thereof broken away to better show the construction; and

Fig. 8 is a transverse section taken on line 8—8, Fig. 7.

The same reference numbers will be used to designate the same parts throughout the several views.

Numeral 1 represents a three wire feeder line which is run along the galleries of the mine, 2 represents the side walls and 3 the rooms in which coal is being mined, while 4 indicates an electric drill or other mining machine which is electrically operated. A flexible cable 5 extends from the machine 4 to the safety switch 6 and is provided at its free end with a plug 7 by means of which the conductor 5 is connected to the switch terminals.

My safety switch consists of a box of wood, metal or any other suitable material. This box has a bottom 8 and a cover 9 hinged to one end of the box by means of hinges 10 (Fig. 2). To the inside of the bottom I secure an insulating switch base 11 which is held in place by means of screws or bolts 12. Secured to the base 8 near each corner thereof are insulating guide posts 13. The base member 11 is preferably of such size that the corners have to be notched for the accommodation of the guide posts. Secured to the switch base 11 are a plurality of pairs of contact clips 14 which may be of the type shown in Fig. 6 or of any other usual type which

is adapted to receive a switch blade. Each clip 14 at the left hand end of the box has electrically connected thereto conductor terminals 15 secured to the ends of conductors 16 whose other ends are electrically connected with the feeder circuit 1. The switch clips 14 in the right hand end of the box (Figs. 2 and 3) have electrically secured thereto tubular socket members 17 having flaring ends 18 as clearly shown in Fig. 2. These sockets serve to receive and form electrical contact with the plug members of the connector plug 7 in the manner hereinafter described. The movable part of the switch consists of an insulating plate 19 which has notches 20 cut out of each corner for the reception of the guide posts 13 (Fig. 4). To the upper side of member 19 I secure a bracket 21 to which the rod 22 is connected by any suitable means. I have shown this rod as made of metal as it well may be, as it is electrically insulated from all live terminals, but where it is desired, it may be made from bakelite hard rubber, fibre or other insulating material. Secured to the outer surface of the cover 9 is a tubular metal member 22 which has two diametrically opposed slots 23 provided at their bottom with notches 24. Within the tubular member 22 and surrounding the rod 21 is a coil compression spring 25 (Fig. 2). A pin 26 extends transversely through the rod 21 and has its ends extending into slots 23. The upper end of spring 25 abuts the pin 26 and tends to hold the plate 19 and associated parts in the full line position shown in Figs. 2, 5 and 6. The upper end of the rod 21 is provided with a spherical hand grip 27 of insulating material. When it is desired to close, the switch rod 21 is moved downwardly until pin 26 comes opposite notches 24, and it is then slightly rotated so that the ends of pin 26 engage the shoulders of the notches 24 and hold the switch closed against the action of spring 26. A slight rotation of rod 21, so as to move the pins 26 out of notches 24, permits the switch to open with a snap. Secured to the lower side of the movable insulating plate 19 are a number of knife blade connectors 28 which are secured thereto by clips 29 in the manner shown in Fig. 6 or in any other substantial manner. When the switch is in closed position, indicated by dotted lines in Fig. 2, knife blades 28 connect members of corresponding pairs of clips 14. The cover 9 may be locked in place by a hasp and staple cooperating with an ordinary padlock as indicated by numeral 30, in Fig. 2.

Connection between the switch and the cable 5 is made by means of a plug member 7 which, in a three wire installation

such as shown, has three plug contacts 31 and 32 which fit into suitable grooves in the adjacent surfaces of the two cooperating members 33 and 34 in the manner clearly shown in Figs. 2 and 7. The two outside plug members 31 are curved at their inner ends, as shown in Fig. 7, and can consequently not be pulled out but the center plug 32 is straight and is therefore provided with an enlargement 35 which prevents longitudinal movement. Plug 7 has a handle portion 36 which permits it to be conveniently manipulated.

The plugs 31 and 32 are spaced the same distance apart as tubular sockets 17 and bushed openings 37 are provided in the end wall of the switch box, through which openings the plugs may be inserted and the ends thereof introduced into the tubular contacts 17. It is essential that the plugs cannot be connected to or removed from the connectors 17 while the switch is in closed position and to accomplish this result I provide the following means:

To the end of the movable insulating switch member 19 I secure a downwardly projecting plate 38 of insulating material. Plate 38 extends downwardly such a distance that when the switch is in closed position the lower edge will almost reach the upper surface of the switch base 11 (see dotted line position in Fig. 2). The lower edge of plate 38 has three notches 39 corresponding to each of the tubular sockets 17. These notches are of such size that plugs 31 and 32 can pass through them. One or all of the plugs are provided near their ends with an enlargement 40 which is so large that it will not pass through the notches 39. If the switch is closed, the plug cannot be connected to the live tubular connectors 17 because the enlargement will engage the plate 38 in the manner indicated in Fig. 2 and in a like manner the plug cannot be withdrawn as long as the switch is closed, as the enlargement is then on the inside of plate 38 and prevents withdrawal. My switch is therefore so constructed that the plug can be inserted and removed only while the switch is open. This insures that the operator cannot be injured by an arc as he connects or disconnects the plug. After the plug is inserted the switch is closed by a downward pressure on the handle 27 and locked in position by a slight turn.

From the above description it will be apparent that I have invented a switch that is especially adapted for use in mines and other places where power is taken from various points along a main feeder line as the connection to the translating device cannot be made while the switch is closed.

Having now described my invention, what I claim is:

1. A switch comprising in combination a

switch box; a cover hingedly connected thereto; an insulating switch base secured to the bottom of the box; a plurality of contact clips secured to said base in pairs; 5 conductors secured to one member of each pair, the other clips of each pair having a tubular connector secured thereto, one end of the box having openings registering with the tubular connections, said openings being adapted to receive plugs which connect with the tubular connectors; an insulating switch base movably mounted in said box; conductors mounted on said base and adapted to connect pairs of contact clips; 10 resilient means cooperating with the movable switch member and tending to hold the switch in open position; a rod extending through the switch box and having one end connected to the movable insulated base 15 whereby the same may be moved from open to closed position; a plate of insulating material secured to one end of the movable plate and adapted to obstruct the passage from said openings to said tubular connectors when the switch is in closed position; and openings in the lower edge of 20 said plate.

2. A switch comprising, in combination, a switch box having a hinged cover; a switch base of insulating material secured to the bottom of said box; a plurality of 25 pairs of contact clips secured to said base,

corresponding clips of each pair having conductors secured thereto, the other clips of each pair having tubular connectors secured thereto, the end of the box nearest the tubular connectors having openings therein through which plug members may be inserted for connection with the tubular connectors; a plurality of guide members 35 secured to the switch bottom and extending upwardly in parallel relation; an insulating member having means for cooperating with said guides; means secured to the insulating member and extending through the 40 cover of the box for moving the insulating member; resilient means comprising a spring for normally holding the insulating member in open position; a plurality of knife blade connectors secured to the under side 45 of the insulating member and adapted to connect the clips of each pair; means for holding the switch closed against the action of said spring; and a plate of insulating material secured to one end of the movable 50 insulating member, said plate being adapted to obstruct the passageway from the tubular connectors to the openings in the end wall so as to prevent the insertion of a plug connector, said plate having a number of 55 notches on its lower edge.

In testimony whereof I affix my signature.

RAPHAËL F. POLI.
